SOLVENT REFINING OF MINERAL OIL

Edward Gardner McFarland, Lawrenceville, Ill.,
assignor to The Indian Refining Company,
Lawrenceville, Ill., a corporation of Maine

Application November 24, 1936, Serial No. 112,475

8 Claims. (Cl. 196—13)

This invention relates to solvent refining of mineral oil, and more particularly to the recovery of the solvent from the refined oil for reuse in the process.

5 In the solvent refining of mineral oil, such as lubricating oil, with a selective solvent of the character of furfural, for example, it is customary to recover solvent from the refined oil by stripping with steam. When lubricating oil, 10 which contains a small percentage of lighter oil fractions such as naphtha, is refined in this manner, the lighter oil or naphtha may be removed in whole or part during the steam stripping operation which is customarily employed to 15 recover the last trace of retained solvent from the refined oil. In order to render such a solvent refining process economical and practical, it is essential that the solvent be recovered substantially completely for reuse so that the solvent loss in the process is kept at a very small amount. The above mentioned steam stripping 20 operation introduces water into the system, and this water must be separated from the solvent prior to reuse of the recovered solvent in subsequent refining operations. This separation of 25 water from the solvent is customarily accomplished by a series of stripping, fractionating and settling operations, so that the water content of the recovered solvent is reduced to a very small figure of the order of less than 0.50%. When lighter oil fractions, such as naphtha, are 30 present in the oil being refined, and these fractions removed in the stripping operation as above described, it is found that this lighter oil carries over into the fractionating and settling 35 operations and interferes with them. Moreover, the accumulation of such lighter oil in the solvent system is objectionable as altering the composition of the solvent and interfering with the 40 refining operations.

It is an object of the present invention to provide an improved method of recovering such a selective solvent substantially free from water and at the same time to remove any lighter oil 45 from the solvent system in a simple and effective manner so that such lighter oil does not interfere with the recovery operations.

In accordance with the present invention, the refined oil containing a portion of solvent is 50 treated to remove that solvent by distillation and steam stripping. The mixture of water vapor, lighter oil vapor and solvent removed in the steam stripping operation is passed to a fractionating zone maintained at a temperature below the boiling point of water at the prevailing

pressure where it condenses to form a lean mixture of primarily water containing a small proportion of the solvent and lighter oil. This mixture is stripped with steam and the vapors consisting of an enriched mixture of solvent and lighter oil with steam are passed to a fractionating zone maintained at a temperature to condense primarily solvent and allow steam and the lighter oil vapors to pass overhead. These overhead vapors are condensed and passed to a 10 decanter where the condensate is allowed to stand and stratify into a light oil layer and a water layer containing dissolved solvent. The light oil is removed at this point from the solvent system and the water layer containing dissolved solvent is returned to the last mentioned fractionating zone to provide reflux therefor. Condensate from this fractionating zone is allowed to stratify into a water layer which is returned to the first mentioned fractionating and 15 steam stripping zone, and the enriched solvent layer is then passed to further settling and drying zones where the water content is reduced to the desired low percentage.

In the drawing, the single figure is a dia- 25 grammatic view of a preferred embodiment of apparatus for carrying out the method of this invention. Referring to this drawing, the oil to be refined is charged through the line 10 by pump 11 and passed through a suitable steam 30 heater 12 where it is indirectly heated by steam to the desired refining temperature. By way of example, this invention is hereinafter described in connection with the refining of a Mid-Continent distillate lubricating oil with furfural, although it is to be understood that the invention can be employed in the refining of other types of distillate and residual oils with any of the selective solvents of the character of furfural, nitrobenzene, phenol, and the like, which are customarily employed. The heated oil at a temperature of the order of 200° F. is introduced by line 13 into the lower portion of the counter-flow treating tower 14 shown as containing four 35 layers of raschig ring packing 15.

Furfural is simultaneously pumped from storage tank 16 by pump 17 through steam heater 18 and a refined oil heat exchanger 19, and then introduced at a temperature of the order of 240° F. by line 20 into the upper portion of 50 tower 14. The ratio of solvent to oil is preferably of the order of 2:1 up to 3:1. The oil rises through the solvent, which latter gravitates towards the bottom of the tower. The furfural is selective as between paraffinic and 55

non-paraffinic constituents of the oil, and dissolves out naphthenic, unsaturated and aromatic hydrocarbons to form an extract mix which settles to the bottom of the tower and is withdrawn to solvent recovery through the line 21. The raffinate of refined oil containing about 10% of furfural dissolved therein rises to the upper portion of the tower from where it is continuously withdrawn by line 22 to a refined oil mix tank 23.

The refined oil mix is withdrawn from tank 23 by pump 24 and forced through a heating coil 25 in the convection bank of a pipe still heater 26. The mix at a temperature of about 270° F. is delivered by line 27 into the upper portion of a refined oil stripping tower 28 provided with an upper series of bubble trays 29 and a lower series of inclined contact trays 30. Oil accumulating in the bottom of the tower is recirculated by pump 31, through line 32 and heating coil 33 in the radiant section of furnace 26 and thence passes at a temperature of about 460° F. by line 34 into an intermediate portion of tower 28 above the inclined contact trays 30. This supplies the main heating of tower 28, which may be operated at a bottom temperature of around 425° F. and a top temperature of around 220° F. and under a vacuum equivalent to an absolute pressure of about 2" of mercury. At these temperatures and with the vacuum maintained therein, most of the furfural is driven off from the refined oil and is drawn as vapor through vapor line 35 to a solvent condenser 36 and then by line 37 into a solvent accumulator drum 38. Vacuum on the system is maintained by dry vacuum pump 39 communicating with the upper portion of solvent drum 38 through vapor line 40.

A small proportion of the solvent is still retained in the oil. This is removed by passing a portion of the oil recirculated by pump 31 through a branch line 41 discharging into the upper portion of a refined oil steam stripper 41 containing bubble trays 43. The amount of oil passed to the stripper 42 is controlled by a float mechanism 44 responsive to the oil level in tower 28. The float mechanism regulates a valve 45 in line 41 to maintain a normal liquid level in tower 28. Stripper 42 may operate at substantially atmospheric pressure with a bottom temperature of around 385° F. and a top temperature of around 175° F. Steam is directly injected into the bottom of stripper 42 by line 46 and serves to strip out remaining traces of solvent and lighter oil vapors from refined lubricating oil. The refined oil is discharged from the base of stripper 42 through line 47, and forced by pump 48 through line 49, refined oil heat exchanger 19, line 50, refined oil cooler 51 and line 52 to storage.

As the solvent is an expensive item of the process it is highly desirable to cut down solvent loss to a minimum. Moreover, as the presence of water above a certain maximum content of about 0.50% in the solvent is objectionable when that solvent is reused for further refining operations, the stripped vapors from stripper 42 are further processed to separate the solvent from the water and to also remove any lighter oil which may be present. As shown, the vapors are passed by vapor line 54 into an intermediate portion of a solvent stripper 55 below a trap tray 56. This tray 56 divides the tower into a lower fractionating zone containing bubble trays 57 and an upper fractionating zone containing bubble trays 58. The temperature within the solvent stripper is

maintained below the boiling point of water at the prevailing atmospheric pressure so as to condense water vapor in the lower fractionating section 57. This condensate which will also contain a small proportion of furfural and light oil passes downwardly from tray to tray in the lower stripping section 57 countercurrent to a rising current of steam introduced by line 59 which serves to sweep out remaining traces of solvent and lighter oil from the water. The steam serves to carry the solvent and lighter oil in vapor form above the trap tray 56 through the center vapor dome thereof and into the upper fractionating section 58. Condensed water substantially devoid of solvent collecting in the base of stripper 55 is discharged by line 60.

The vapors thus introduced into the upper fractionating section 58 consist of an enriched mixture of furfural and steam with any lighter oil vapor which may be present. Adequate refluxing is provided for this upper fractionating section of the stripper in order to condense primarily furfural therein. The temperature of this section of the tower is regulated by the supply of reflux so that mainly the highest boiling constituent, namely the furfural, is condensed as the vapors are fractionated therein, while a lean mixture of primarily steam with some furfural vapor and any light oil vapor passes overhead by vapor line 61 to a condenser 62. The condensate flows into a decanter 63 where it is allowed to stand and stratify into a lower water layer containing dissolved furfural and an upper light oil or naphtha layer. The light oil layer is discharged from the upper portion of decanter 63 through line 64 and is thus removed from the system. The lower water layer is returned from the lower portion of decanter 63 through line 65 into the upper portion of solvent stripper 55 above trays 58 to supply reflux for this upper fractionating section. In explanation, it may be pointed out that the vapors passing overhead through line 61 consist mainly of steam with only a small proportion of furfural. Under these conditions, the furfural in the condensate passed to decanter 63 is dissolved substantially completely in the water layer, while the condensed lighter oil or naphtha will be substantially immiscible with this water layer and thus can be removed without appreciable loss of solvent.

The condensate from the upper stripping section 58 of solvent stripper 55 accumulates on trap tray 56 and there stratifies into an upper water layer containing only a small proportion of dissolved furfural and a lower furfural layer containing only a small proportion of water. The upper water layer is allowed to overflow through the dome of the trap tray and thus be returned to the lower stripping section 57 as reflux, and the small proportion of furfural dissolved in this water so returned is then stripped out by steam introduced at 59 so that this solvent is eventually recovered. The lower furfural layer is continuously discharged by line 66 and passed through a solvent cooler 67 into an accumulator drum 68. It is here allowed to stand and further stratify into an upper water layer containing a small proportion of dissolved furfural and a lower furfural layer containing a very small proportion of dissolved water. The upper water layer which is comparatively rich in furfural is returned by line 69 to the upper fractionating section 58 of solvent stripper 55 to be reprocessed and to furnish additional reflux. The lower furfural layer is passed from accumulator drum 68 75

through line 70 into a dryer 71 where it is indirectly heated by steam coils to a temperature above the boiling point of water to vaporize remaining traces of water in the solvent. This 5 vapor is removed by vapor line 72 to a condenser 73, and the condensate then returned by pump 74 and line 75 to the upper fractionating section 58 of solvent stripper 55 for reprocessing and to provide additional reflux.

10 The dried solvent is discharged by line 76 through solvent cooler 77 into a sample accumulator drum 78. The latter is equipped to remove samples at regular intervals to see that the solvent is on test and that the water content is 15 below the maximum allowable. If it is on test, it is passed by line 79 to the solvent accumulator drum 38 where it is added to the solvent recovered in the refined oil stripping tower 28. Recovered solvent overflows from accumulator 20 drum 38 into an overflow drum 80, from the bottom of which it is withdrawn by pump 81 and forced through line 82 to the solvent storage tank 16 for reuse in the process. Makeup solvent may be added as needed to tank 16 by line 83 to compensate for solvent loss.

25 In order to recover any uncondensed solvent vapors withdrawn from the accumulator drum 38 through vapor line 40 by the vacuum pump 39, the discharge from the vacuum pump is forced by vapor line 84 through an after-cooler 85 into a solvent drip drum 86 where condensed solvent drops out of the vapors. This solvent is passed by line 87 into a sump solvent tank 88. Uncondensed vapors are removed from drum 86 30 by vapor line 89 opening into the upper portion of sump solvent tank 88, where any further condensate drops out of the vapors. Remaining non-condensable gases escape from tank 88 by vent 90. This recovered solvent is returned from 35 tank 88 by pump 91 through line 92 to the upper portion of the lower fractionating section 57 of solvent stripper 55 for reprocessing. In case the solvent in sample accumulator drum 78 is not on test, it may be passed by line 93 into the sump solvent tank 88 from where it is returned by 40 pump 91 and line 92 to the solvent stripper 55 for reprocessing.

45 In this manner, the solvent is effectively recovered from the refining operation, while at the same time water and light oil are continuously removed from the system. The solvent loss is therefore reduced to about 0.02% or less of the solvent handled. While the invention has been described by way of example in connection with the recovery of solvent from the raffinate or 50 refined oil from counterflow tower 14, it is to be understood that the invention is applicable to the recovery of solvent in a similar manner from the extract mix discharged by line 21. This extract mix may be passed through a heater and then to an extract stripping tower and finally to an extract steam stripper in the manner described above in connection with the recovery of solvent from the raffinate. The dry solvent 55 removed by the extract stripping tower may be passed through a condenser and then into the solvent accumulator drum 38. The wet solvent recovered by the extract steam stripper may be passed by a vapor line to the solvent stripper 55 for processing in the manner described above, so that the solvent stripper and related apparatus for drying of the solvent is common to the processing of wet solvent recovered from both the raffinate and the extract. As this apparatus is 60 substantially identical with that shown for the

recovery of solvent from the refined oil, further illustration thereof is thought unnecessary and it has purposely been omitted to avoid duplication and effect simplification of the drawing. Wherever the expression "solvent recovered from the refined oil" is employed, throughout the description and claims, it is to be understood that this refers to the recovery of solvent from the so-called extract as well as from the so-called raffinate. While the invention has been specifically described in connection with the use of furfural as the refining solvent, it is to be understood that the invention is also applicable to the recovery of other solvents customarily used in the solvent refining of mineral oil and which are selective as between paraffinic and non-paraffinic constituents of the oil.

65 Obviously many modifications and variations of the invention, as hereinbefore set forth, may be made without departing from the spirit and scope thereof, and therefore only such limitations should be imposed as are indicated in the appended claims.

I claim:

1. In the solvent refining of heavier mineral lubricating oil containing some lighter oil with a solvent which is partially miscible with water and which is highly selective between paraffinic and non-paraffinic hydrocarbons, and wherein the solvent is recovered from the refined oil by 25 steam stripping to produce a lean water mixture containing solvent and lighter oil, the method in the separation of the solvent from the water and lighter oil of said mixture which comprises stripping the solvent and lighter oil with steam from 30 said lean mixture of the same in water in a stripping zone, passing the stripped vapors enriched in solvent to a fractionating zone and condensing solvent therein, removing a lean mixture of uncondensed vapors consisting primarily 35 of water together with some solvent and lighter oil vapors from the fractionating zone and condensing them, passing the condensed lean mixture to a settling zone where the condensate stratifies into a water layer containing solvent 40 dissolved therein and a lighter oil layer, removing the lighter oil layer, returning the water layer containing dissolved solvent as reflux to the fractionating zone, separating a water layer from the condensed solvent layer in the fractionating zone and returning the water layer to the stripping zone, removing condensed solvent from the fractionating zone, and removing water substantially free from solvent from the lower portion 45 of the stripping zone.

2. The method of claim 1, wherein condensed solvent from the fractionating zone is passed to an accumulating zone where it is allowed to settle and stratify into an enriched solvent layer and a lean water layer, and the water layer is 50 returned to the fractionating zone to provide additional reflux.

3. The method of claim 1, wherein condensed solvent from the fractionating zone is passed to an accumulating zone where it is allowed to settle and stratify into an enriched solvent layer and a lean water layer, the water layer is 55 returned to the fractionating zone to provide additional reflux, the enriched solvent layer is passed to a drying zone where it is heated to drive off 60 retained water in the form of steam mixed with some solvent vapor, and the mixed vapors from the drying zone are condensed and the condensate returned to the fractionating zone for 65 reprocessing.

4. The method of claim 1 wherein the temperature of the fractionating zone is controlled to condense primarily solvent therein and to allow water vapor and lighter oil vapor mixed with some solvent vapor to pass overhead and be removed from the fractionating zone for condensation into a lean water mixture with which the lighter oil is substantially immiscible so that it will stratify as a separate layer while the solvent will be substantially completely dissolved in the condensed water.

5. In the solvent refining of mineral lubricating oil containing some lighter oil with furfural, and wherein furfural is recovered from the refined oil by steam stripping to produce a lean water mixture containing furfural and lighter oil, the method in the separation of furfural from water and lighter oil of the said mixture which comprises stripping the furfural and lighter oil with steam from said lean mixture of the same in water in a stripping zone, passing the stripped vapors to a fractionating zone and condensing furfural therein, removing a lean mixture of vapors consisting primarily of water vapor containing lighter oil vapor and a small proportion of furfural vapor from the fractionating zone and condensing them, passing the condensate to a settling zone to stratify into an upper lighter oil layer and a lower water layer containing furfural dissolved therein, removing the lighter oil layer, returning the water layer containing dissolved furfural as reflux to the fractionating zone, separating a water layer from the condensed furfural layer in the fractionating zone and returning the water layer to the stripping zone, removing condensed furfural from the frac-

tionating zone, and removing water substantially free from furfural from the lower portion of the stripping zone.

6. The method of claim 5, wherein condensed furfural from the fractionating zone is passed to an accumulating zone where it is allowed to settle and stratify into a lower enriched furfural layer and an upper water layer containing a small proportion of dissolved furfural, and the upper water layer is returned to the fractionating zone to provide additional reflux.

7. The method of claim 5, wherein the condensed furfural from the fractionating zone is passed to an accumulating zone where it is allowed to settle and stratify into a lower enriched furfural layer and an upper water layer containing a small proportion of dissolved furfural, the water layer is returned to the fractionating zone to provide additional reflux, the enriched furfural layer is passed to a drying zone where it is heated to drive off retained water as steam mixed with some furfural vapor, and the mixed vapors from the drying zone are condensed and the condensate returned to the fractionating zone for reprocessing.

8. The method of claim 5, wherein the furfural and lighter oil are stripped with steam from the lean mixture at a temperature below the boiling point of water at the prevailing pressure, and wherein the temperature of the fractionating zone is controlled to condense primarily furfural therein and to allow water vapor and lighter oil vapor mixed with a small proportion of furfural vapor to pass overhead and be removed from the fractionating zone before condensation thereof.

EDWARD GARDNER McFARLAND.
